UNITED STATES PATENT OFFICE.

JOHN W. BEARD, OF INDIANAPOLIS, INDIANA.

HYDROCARBON-BURNER.

1,210,031.

Specification of Letters Patent.

Patented Dec. 26, 1916.

Application filed April 20, 1916. Serial No. 92,506.

To all whom it may concern:

Be it known that I, JOHN W. BEARD, a citizen of the United States, residing at Indianapolis, in the county of Marion and 5 State of Indiana, have invented a new and useful Hydrocarbon-Burner, of which the following is a specification.

The device forming the subject matter of 10 this application is adapted to be employed for converting liquid fuel, such as kerosene oil, into gas.

The invention aims to provide a structure 15 of this sort in which there will be no puffing or thumping, owing to the peculiar disposition of certain pipes which form parts of the oil conduits.

Another object of the invention is to provide a structure of this sort which may be assembled at a minimum expenditure of 20 labor, the number of couplings being reduced.

A further object of the invention is to improve the construction of the combined deflectors and generators, so as to facilitate the 25 assembling of the structure.

It is within the province of the disclosure to improve generally and to enhance the utility of devices of that type to which the present invention appertains.

With the above and other objects in view 30 which will appear as the description proceeds, the invention resides in the combination and arrangement of parts and in the details of construction hereinafter described and claimed, it being understood that 35 changes in the precise embodiment of the invention herein disclosed can be made within the scope of what is claimed without departing from the spirit of the invention.

In the accompanying drawings:—Figure 40 1 shows the invention in perspective; Fig. 2 is a cross section showing one of the combined deflectors and generators; and Fig. 3 is a section taken on the line 3—3 of Fig. 2.

In carrying out the present invention 45 there is provided a vertical oil supply pipe 1 connected with one branch of a cross 2. Assembled with the lateral branches of the cross 2 are horizontal alined nipples 3 united with elbows 4 with which are assembled upwardly 50 vertical pipes 5 located in a common plane, the pipes 5 at their upper ends carrying valve casings 6 and 7. The casings 6 and 7 are equipped with horizontally disposed hand valves 8. Assembled with the 55 vertical, upwardly projecting branch of the

cross 2 is a nipple 9 carrying a casing 10 provided with a vertical hand valve 11. Assembled with the rear ends of the valve casings 10 and 7 are nipples 12 united with 45° elbows 14, with which are connected upwardly 60 extended pipe sections 15 and 16, the pipe sections 15 and 16 being disposed at an angle of 45° to the horizontal. Connected with the upper ends of the pipe sections 15 and 16 are elbows 17 and 18. Connected with the elbow 18 is a horizontal T 19. Projecting from the T 19 is a horizontal pipe 20. The pipe 20 is provided at its rear end with an elbow 21, and projecting from the elbow 21 at right angles to the 70 pipe 20 is a pipe 22. One end of the pipe 22 is equipped with an elbow 23 carrying a burner tube 24, disposed parallel to the pipe 20 and in a common plane therewith. One end of the burner tube 24 is closed by a cap 75 25. Intermediate the cap 25 and the elbow 23, the burner tube 24 is supplied with a burner orifice 26 which discharges laterally.

Projecting laterally from the T 19 and disposed in a common plane with the pipes 80 20 and 22 is a pipe 27 provided with an elbow 28 carrying a burner tube 29 having a burner orifice 30, and closed at one end by a cap 31. The burner tubes 29 and 24 project in opposite directions, and preferably 85 are alined axially.

The numeral 32 designates a combined deflector and generator, preferably of circular contour, and equipped with an internal chamber 33. The top 34 of the deflector and 90 generator 32 is provided with a depending rib 35 having a smooth opening 36 of sufficient size so that the pipe 27 may be slid freely and readily through the opening before the pipe is threaded into the T 19. At 95 the ends of the opening 36, collars 38 are formed. There is provided a short tube 37 disposed at right angles to the pipe 27, whereby communication is established between the elbow 17 and the chamber 33. 100 Projecting from the deflector and guard 32 in axial alinement with the tube 37 is a short pipe section 39 connected with an elbow 40 carrying a vertical, depending pipe 41 assembled with an elbow 42 carrying a 105 horizontal burner tube 43 located below the deflector and generator 32. The burner tube 43 is closed at one end by a cap 44 and intermediate its ends is provided with a burner orifice 45 disposed below the geometrical 110

center of the deflector and guard 32. The burner orifice 45 discharges upwardly against the lower surface of the member 32.

The numeral 46 designates a priming pan 5 having end walls 47 provided with openings 48 whereby the priming pan may be suspended from the burner tube 43, it being possible to mount the priming pan on the tube 43 by removing the cap 44.

10 Projecting from one end of the valve casting 6 is a pipe 49 having an upwardly inclined extension 50 disposed at an angle of 45° to the horizontal, the extension 50 corresponding to the pipes 15 and 16, the pipe 15 49 being long enough so that its extension 50 is disposed rearwardly of the deflector and generator 32. The extension 50 of the pipe 49 is connected as shown at 51 to a combined deflector and generator 52, constructed like 15 the member 32, the parts 37 and 17 of Fig. 2 being noted at this point. The pipe 22 passes slidably through the deflector and generator 52, in the same way that the pipe 27 passes through the deflector and generator 32. Connected with the member 52 20 is a short pipe section 53, corresponding to the short pipe section 39. On the short pipe section 53 is an elbow 54 united with a depending pipe 55, corresponding to the pipe 41 and in a common vertical plane therewith. The pipe 55 is connected to an elbow 56 carrying a burner pipe 57 closed at one end by 25 a cap 58, the pipe 57 having a burner orifice 59 disposed directly below the geometrical center of the deflector and generator 52. A priming pan 60 is suspended from the burner pipe 57, in the manner hereinbefore set forth.

One of the advantages of the present 40 structure rises out of the ease with which it may be assembled. All of the parts may be set up complete with the exception of the pipes 27 and 22. These pipes may then be slid, respectively, through the openings in 45 the generators 32 and 52 and be threaded, respectively, into the T 19 and the elbow 21. It is therefore unnecessary to place couplings or unions in the pipes 15 and 20, and the danger of leakage is reduced to a minimum.

50 Oil enters the structure by way of the pipe 1 and flows by way of the pipe 15 and the pipe 27 to the burner tube 29. Oil also flows by way of the pipes 9 and 16 to the 55 chamber 33 of the generator 32, the fluid passing thence by way of the pipes 39 and 41 to the burner tube 43. The flame burning at the orifice 45 heats the generator 32, and consequently, the oil is converted into gas before it passes to the burner tube 43 or to 60 the burner tube 29. The flame at the burner orifice 45 is deflected by the member 32 and rises to heat pots, etc., on the lid-holes of a range. The flame at the burner orifice 30 flows laterally and may be employed for

heating an oven, the structure being of peculiar utility and used in connection with a cooking range.

Oil from the pipe 15 passes by way of the pipe 20 and the pipe 22 to the burner tube 70 24. From the pipe 5, oil enters the pipe 49 and passes through the extension 50 into the interior chamber of the generator 52, and thence passes to the burner tube 57, by way of the pipes 53 and 55. The operation carried out adjacent the generator 52 is the same as that carried out adjacent the generator 32.

Especial attention is directed to the fact that the pipes 15, 16 and 50 are inclined at 80 an angle of approximately 45° to the horizontal, and do not stand vertically. Owing to this construction, the burners will operate without puffing and pounding. The oil in the pipes 15, 16 and 49 is agitated to a considerable extent, and it has been found that when elements corresponding to the pipes 15, 16 and 50 stand vertically, a burner of this type will operate with a puffing, pounding and jarring action, which is not present in 90 the structure forming the subject matter of this application.

There is advantage in disposing the burner tubes 24 and 29 transversely of the pipes 22 and 27 respectively, and in placing the 95 burner orifices 26 and 30 intermediate the ends of the burner tubes. Owing to this construction, the tubes 24 and 29 may be cleaned out readily, and there is room at the ends of the burner tubes for accumulating 100 sediment from the fuel.

Having thus described the invention, what is claimed is:—

1. In a device of the class described, a generator comprising a chamber and including 105 a top having a depending rib provided with a smooth opening therethrough; a first fuel pipe located in advance of the generator and opening into the chamber; a U-shaped pipe located opposite to the first pipe and opening 110 into the chamber, the U-shaped pipe including a burner tube disposed below the generator and having a combustion orifice located below the generator; a second fuel pipe located to one side of the generator and disposed approximately parallel to the first pipe; a cross pipe slidably freely through the smooth opening in the generator and detachably assembled at one end with the said second fuel pipe; a transverse burner tube at 115 the other end of the cross pipe and provided with a burner orifice; and means for supplying fuel to the first and second pipes.

2. In a device of the class described, a generator comprising a chamber and including 120 a top having a depending rib provided with a smooth opening therethrough; a first fuel pipe located in advance of the generator and opening into the chamber; a U-shaped pipe located opposite to the first pipe and open- 125

ing into the chamber, the U-shaped pipe including a burner tube disposed below the generator and having a combustion orifice located below the generator; a second fuel pipe located to one side of the generator and disposed approximately parallel to the first pipe; a cross pipe slideable freely through the smooth opening in the generator and detachably assembled at one end with said second fuel pipe; a transverse burner tube at the other end of the cross pipe and provided with a burner orifice; and means for sup-

10

plying fuel to the first and second pipes, the first and second pipes being upwardly inclined, at an angle of approximately 45° , 15 from said means toward the generator.

In testimony that I claim the foregoing as my own, I have hereto affixed my signature in the presence of two witnesses.

JOHN W. BEARD.
